UNITED STATES PATENT OFFICE.

WILDER P. BOWERS, OF CHICAGO, ILLINOIS.

INTERNAL-COMBUSTION MOTOR.

1,245,861.

Specification of Letters Patent.

Patented Nov. 6, 1917.

Application filed November 1, 1916. Serial No. 128,966.

To all whom it may concern:

Be it known that I, WILDER P. BOWERS, citizen of the United States, residing at Chicago, in the county of Cook and State of Illinois, have invented certain new and useful Improvements in Internal-Combustion Motors; and I do hereby declare the following to be a full, clear, and exact description of the invention, such as will enable others skilled in the art to which it appertains to make and use the same.

This invention relates to improvements in internal combustion motors, and more particularly to means for introducing water or vapor into the cylinders thereof simultaneously and admixed with the carbureted air for the usual and well-known purpose of eating out existing carbon deposits in the cylinders, and preventing such deposits

20 therein.

The main object of the present invention is to provide a very simple and efficient device for attaining the aforesaid objects, and in which the feed of water or vapor is readily controlled by the operator from his seat in a motor-propelled vehicle to which the device

25 is particularly adapted.

A suitable embodiment of the invention is illustrated in the accompanying drawings

30 in which:

Figure —1— is a fragmentary view partly in section and partly in elevation of the hood and motor of an automobile including the dash-board of the latter equipped with

35 an apparatus constructed in accordance with

my invention.

Fig. —2— is a detail transverse section of a water tank employed.

Fig. —3— is a detail view in elevation

40 showing a dial and indicating hand associated with the valve controlling the supply

from the tank to the motor.

My said invention comprises a tank 1 adapted to contain water, which may be

45 mounted at any suitable point, preferably on the dash-board, of a motor-propelled vehicle. Leading from the bottom of the tank 1 to a point higher than the latter is a pipe 2 which is coiled between its ends, as indicated at 3, about the exhaust manifold 4 of the motor, and which is connected at its other end, preferably by means of branch pipes 5, with the intake manifold 6 of the motor so as to uniformly distribute water or

55 vapor supplied by said pipe 2 to said intake

and among the several cylinders of the motor. In this instance I have illustrated an ordinary four-cylinder motor, but it will be obvious that my said device may be applied with equal advantage to motors having a greater or less number of cylinders.

Between the ends of the pipe 2 is a valve-housing 7 containing a needle-valve or other suitable valve for controlling the passage of water through said pipe. The stem 8 of this needle valve projects through an opening in the dash-board 9, and is provided at said end with a suitable knob or other manually engageable part 10 which is equipped with an indicating hand adapted to indicate on the graduated scale 12, contained on a disk or dial 13 mounted on said dash-board, the extent to which the said needle valve is open. In the instance illustrated the indicating hand 11 indicates at zero on the dial showing that the valve is closed. By turning the knob 10 to the right the said valve may be very slightly opened, or opened to a considerable extent, depending upon the amount of water or vapor desired to be introduced into the intake manifold and engine cylinders. Obviously the water must be drawn from the tank 1 by the communication of the partial vacuum existing in the intake manifold, during operation of the motor, to the tank 1; thus drawing a supply of water into the pipe 2. If the quantity admitted is very small, as by only very slightly opening the needle valve, such water will be almost instantly converted into steam in the coil 3, which is heated to a high degree by the exhaust manifold and the steam or vapor thus generated will be drawn into the intake manifold; and thus into the cylinders together with charges of carbureted air entering the same. The result of the introduction of such vapor is well known and requires no particular mention or description here. By further opening the needle-valve the supply of water will be increased possibly to such an extent as to completely fill the coil 3 with water which will become heated therein, and will then pass in such heated condition into the intake manifold where by reason of the existing vacuum, it will be converted into vapor or so-called wet steam which is advantageously introduced when the motor attains a high temperature, and the carbon deposits therein are unusually great and required to be quickly and completely removed.

While I have shown a suitable location for the tank 1, it will be obvious that in many instances it would be still more advantageous to locate the same below the level of the connection of the pipe 2 with the intake manifold so as to prevent a continuous siphon-flow into the manifold when the motor is idle in the event that the operator should forget to close the needle valve.

10 I prefer to employ a needle valve, but any valve capable of relatively fine adjustment will be adapted to the purpose.

While I have shown a suitable embodiment of the invention in the accompanying drawings, it will be obvious, of course, that the same is capable of variation and modification to adapt it to different motors and vehicles without departing from the invention as defined in the appended claim.

20 I claim as my invention:

In a propelling device for internal combustion automobiles, an internal combustion motor, a hood covering same; a cylindrical tank mounted in the space between the said motor and the hood and adapted to contain water, a connecting pipe therefrom

leading to a valve-casing, a needle valve associated therewith and adapted to control the flow of water from the said cylinder tank, a handle for the said valve-stem extending through the dash-board of the car, a knob and pointer associated therewith; a dial associated with the said pointer adapted to indicate the radial position of the said valve-stem, a pipe coil leading away from the valve-casing; said coil being wrapped around the exhaust manifold of the motor, a continuation of the said pipe coil, duplicate branches leading therefrom, an intake main to the said motor, holes in the intake main adapted to receive the said pipe connection and fastening means associated therewith whereby the branch inlets of the previously mentioned water-pipe are connected to the said manifold.

In testimony whereof I have signed my name in presence of two subscribing witnesses.

WILDER P. BOWERS.
